BIRRELL SILENT MOTOR CO., INC., OF CHICAGO, ILLINOIS, A CORPORATION
OF ILLINOIS.

VALVE.

1,288,811

Specification of Letters Patent. Patented Dec. 24, 1918.

Application filed January 29, 1918. Serial No. 214,378.

To all whom it may concern:

Be it known that we, WILLIAM BIRRELL and JAMES BIRRELL, citizens of the United States, residing at Chicago, in the county of Cook and State of Illinois, have invented certain new and useful Improvements in Valves, of which the following is a specification.

This invention relates to valves of the puppet type adapted for use in explosive or internal combustion engines.

Great difficulty has been encountered in the operation of internal combustion engines in obtaining and maintaining a perfect seating of the valves, since as heretofore generally used, so far as we are aware, the valve has been constructed of a solid body the seating face of which must be absolutely true with the valve seat—any irregularity of which valve face with respect to the valve seat—seriously affecting the compression in the cylinder with a resultant deterioration of the power and effectiveness of the engine. Also, the solid non-yieldable valve head seating against the rigid non-yielding valve seat, tends to quickly wear either the valve face or the valve seat, necessitating frequent grinding of either the valve or its seat, or both, and also causing the cylinder to "carbon" much more rapidly than occurs when a perfect seating of the valve with its valve seat is maintained.

The primary objects of our invention are the provision of a valve of the type described which will overcome the defects as above pointed out, due to the use of the "solid" type of valve; to produce a valve the body of valve *per se* of which is formed of laminæ pressed and held firmly together, a portion of the valve however being sufficiently yielding to cause it to effect a perfect seating even though the valve seat may be somewhat worn or irregular.

It is a further object of our invention to provide a valve of the type described that will require no re-facing after once being fitted to its seat; and which, by reason of the comparatively soft yielding blow with which it engages its seat will not wear the seat, and thus prolong the life of both the valve and the valve seat. Further, to provide a valve which by reason of its construction, practically eliminates all so-called

"pound" in engines of the internal combustion type.

Our invention is particularly adapted for use in high speed internal combustion engines such as are used in automobiles, aeroplanes and the like in which the valves are subjected to extremely hard usage, but is as well adapted for use in all instances where valves of this type are employed.

In the accompanying drawings, we have illustrated a practical embodiment of the invention as the same has been practised by us, it being understood that in the adaptation of the invention to specific types of engines, changes in the shape or form and details may be made without departing from the spirit or scope of the invention as claimed.

In the drawings, forming a part of this specification, like numerals of reference indicate like parts throughout the different views of the drawings, in which:

Figure 1 is a view partly in side elevation, and partly in vertical section, of a valve constructed in accordance with our invention, the stem being broken away;

Fig. 2 is a top plan view of the valve;

Fig. 3 is a plan view of one of the laminæ from which the valve body is formed, showing by dotted lines how the slits in the laminæ are staggered;

Fig. 4 is an edge view of a plurality of laminæ further showing the staggered arrangement of the slits in successive laminæ; and

Fig. 5 is a central transverse sectional view of the valve body.

As is well known, in valves of the type here involved, the valve body or head is carried upon a stem which is reciprocated to unseat from, and seat the valve body or head upon the valve seat of the engine cylinder. As our invention concerns only the structure of the valve body, or head *per se*, a showing, or detail description of means for operating the valve is unnecessary.

In the drawings, 5 indicates the valve stem here shown as provided near its outer end with a shoulder or ledge 6 constituting a seat upon which the laminæ or plates making up the valve body or head are mounted. This shoulder or ledge is here shown as angular in form and integral with the stem; obviously this may be varied if found ex-

pedient. The portion 5^a of the stem that projects beyond the shoulder 6 is here shown as hollow, and the valve body, later described, is mounted on this hollow extension, and the extreme end of the latter then flanged over as shown at 5^a. To clamp the valve body in position, the bore of the extension is hexagonal or other similar shape in order to receive a tool for changing the 10 position or adjusting the valve.

The valve body or head designated by the numeral 9 is made up of laminæ or thin metal plates superposed one on the other upon a base plate 10 that is mounted on the shoulder 6, the metal plates forming the valve body or head being securely clamped down and bound between the base plate 10, and a top or outer plate 11, by the turned over end or flange 5^a.

20 The laminæ from which the valve body are formed are radially slit from the periphery inwardly approximately three-fourths of the distance between the periphery and the central opening 7. A number of these slits or cuts as 8 are made in each of the laminæ, and when the sheets are assembled in superposed relation, the slits in each sheet are staggered with relation to the adjacent sheet or sheets so that in no 25 two sheets that are in engagement with each other will the slits in one sheet register with those of the contacting sheet. These slits are for the purpose of providing a more flexible and resilient surface, and also to 30 prevent excessive warping of the laminæ.

In construction, the parts are assembled, the laminæ being tightly clamped together, and then turned down in a lathe to form the 35 face 12 of the valve head that is to engage the valve seat. In the turning-down or 40 shaping of the valve head, the base plate 10 is acted upon by the lathe tool, and given the proper peripheral bevel along with the laminæ or sheets forming the valve body, it being understood that the plate 10, in 45 practice, is within the diameter of the valve seat, and does not engage such valve seat, the seating engagement of the valve head with the valve seat being on the beveled periphery or face 12 of the valve head.

In manufacture of the valve, we have found that the shaping of the valve head is most effectively accomplished by turning-down the same in a lathe instead of by 50 buffing or grinding the same to shape. The action of the turning-down tool on the tightly clamped laminæ imparts to the beveled periphery or face 12 of the valve head a practically solid appearance to the eye, 55 and gives a smooth seating surface for engagement with the valve seat. In use, however, it is to be observed that the point of seating engagement of the valve head being outside the periphery of both plates 10 and 60 11, there is provided a flexible, yielding sur-

face or portion which readily "gives" or flexes under pull on the valve stem, so as to cause the valve head to "hug" the valve seat and effect a seating engagement over the entire surface of the seat. This has been 70 found in practice to occur, even though the valve seat be worn at one or more points so as to render same irregular—the valve head flexing at the low or high points of the seat to effect perfect engagement without in 75 any way interfering with perfect seating throughout the remainder of the valve seat area.

By this construction there is provided a valve body or head having a central portion 10^a which, in the present illustration, is that portion within the periphery of the disk 11, and also having a marginal seating-portion 10^b, being the portion of the laminæ lying outside the periphery of the disk 11. 80 Since the marginal seating-portion 10^b is outside the clamping action of plates 10, and 11, its resiliency is materially greater than that of the central portion, the periphery of disks 11 and 10 however extending to such a point that the laminæ are 85 firmly held in their superposed relation. The slitting of the laminæ not only provides for a more flexible and resilient surface, and materially obviates warping, but 90 also tends to effect and insure a true seating surface at all temperatures and to be so resilient as to cause the valve to be practically noiseless in its operation.

In practice, the laminæ used are of 100 treated steel, sufficiently hard to withstand the use to which such valves are subjected and we have found the same to have practically no wearing effect upon the valve seat, obviating the necessity for frequent 105 grinding of the latter, and materially increasing its longevity. This is due to the flexibility of the valve head and the yielding blow delivered upon the valve seat in 110 the seating stroke of the valve.

With a construction as herein shown, should the laminæ be injured from any cause, new laminæ, or an entire new valve head may be easily substituted for the damaged one as will be obvious.

115 What we claim as new is:

1. A valve comprising a valve stem provided near its outer end with a shoulder, a disk base-plate of relatively greater diameter than the valve stem mounted on the shoulder, a laminated tapered valve head, formed of a multiplicity of superposed thin metal plates of gradually increasing diameter whose peripheries are adapted to touch a valve seat, mounted on the base-plate, each having a plurality of radial slits extending inwardly from the periphery thereof, the thin plates being superposed on the disk base-plate with the slits of the thin plates in staggered relation, a clamp 120

ing plate on the valve head of relatively smaller diameter than the base-plate, and means carried by the stem for binding the valve head on the stem between the base-plate and the clamping plate.

2. A puppet valve comprising a tapered laminated valve head composed of a plurality of centrally apertured thin metal laminæ each adapted to have its periphery touch a valve seat and having a plurality of radial slits extending inwardly from the

periphery thereof, a valve stem extending through the central apertures in the plates, the plates being mounted in superposed relation with the slits in each plate in staggered relation to the slits in adjacent plates, and means to confine the laminæ on the stem. 15

In testimony whereof we affix our signatures.

WILLIAM BIRRELL.
JAMES BIRRELL.
